DESCRIPTION

FIG. 1 is a perspective view of an aerosol medication delivery inhaler body showing our new design;
 FIG. 2 is a front view of the body FIG. 1;
 FIG. 3 is a rear view of the body FIG. 1;
 FIG. 4 is a top view of the body FIG. 1;
 FIG. 5 is a right side view of the body FIG. 1 and which is a mirror image of the left side view of the body of FIG. 1; and,
 FIG. 6 is a bottom view of the body FIG. 1.
 The broken lines in FIGS. 1–6 are for environmental purposes only and form no part of the claimed design.
